9 Claims. (Cl. 74—190)

The present invention relates generally to phonographs. More particularly, the invention relates to that type of phonograph which serves to reproduce sound from a disk type record and as its principal components comprises a horizontally disposed base plate, a turntable over the base plate and with a depending annular flange, a pivotally mounted needle-carrying tone arm in associated relation with the turntable, a single speed electric motor beneath the base plate, a comparatively large, laterally movable, horizontally disposed spring-biased idler wheel adjacent to the depending annular flange on the turntable, and a multi-speed driving mechanism between the armature of the motor and the idler wheel whereby the turntable may be selectively driven at a low speed, one or more intermediate speeds, and a high speed, depending upon the character or design of the record to be played.

More specifically, the invention is concerned with phonograph turntable driving mechanisms of the type wherein the driving connection between the armature and the turntable is predicated upon the tractional engagement of an idler wheel with either the armature shaft itself, or with a stepped drive wheel rotatable with the armature shaft in a selective manner, while at the same time the idler wheel is maintained in tractional engagement with a peripheral region of the turntable so that the idler wheel, by virtue of its dual tractional engagement with both the armature shaft or stepped drive wheel and the turntable, will translate the rotary movement of the armature into rotary movement of the turntable.

Another object of the invention is to provide a phonograph of this type which is an improvement upon, and has certain inherent advantages over, previously designed phonographs and is characterized by the fact that the multi-speed driving mechanism between the armature of the single speed electric motor and the idler wheel is of new and improved construction, embodies a simple and novel arrangement of parts, and has extremely high efficiency.

One object of the invention is to provide a phonograph of the aforementioned type and in which there is an improved manual control arrangement for effecting in a selective manner the various speed changes of which the multi-speed driving mechanism is capable of assuming.

The phonograph of the present invention is of the same general type as that shown and described in my prior patent, No. 2,650,504, dated September 1, 1953 and entitled "Phonograph With Three Speed Turntable Driving Mechanism" and embodies certain inherent improvements, in the main, relating to a novel composite drive wheel construction for translating the rotary motion of the armature of the electric motor to the turntable, a novel means for disengaging the drive wheel from the turntable during actual speed change operations, and novel manual control instrumentalities for effecting such disengagement between the drive wheel and turntable and for effecting selectively the desired speed change operations.

For approximately the past twelve years, disk type phonograph records appearing on the market have been designed for turntable speeds of 33½ r.p.m., 45 r.p.m. or 78 r.p.m. and the phonograph shown and described in

2

my above mentioned patent is predicated upon such turntable speeds. In comparatively recent times, record manufacturers have placed upon the market a disk type record designed for use with a turntable capable of being rotated at a speed of 16½ r.p.m., thus producing a record of exceptionally long playing characteristics. The record player or phonograph of the present invention is designed to accommodate records which are designed for rotation at any of the four speeds mentioned above, and toward this end, it embodies a novel drive wheel assembly by means of which such turntable speeds may be selectively attained.

In order to produce the relatively slow turntable speed of 16½ r.p.m. by ordinary means, i.e., utilizing a conventional stepped drive wheel having drive wheel sections of varying diameters, an extremely wide range of diameters would have to be employed either for the stepped portions of the drive wheel or for the diameter of the idler wheel, rendering the latter unduly large. If the diameter of the drive wheel were to be maintained within normal limits, the diameter of the armature shaft or of the smallest step on the drive wheel would of necessity be extremely small so that inadequate traction would be attained between the shaft or drive wheel and the idler wheel. According to the present invention, in order to attain the necessary speed reduction for a turntable drive of 16½ r.p.m. a novel form of composite idler wheel assembly is employed having two traction treads of different diameters, one of the treads being selectively engageable with the armature shaft or stepped drive wheel carried thereby and the other tread being engageable with the turntable, the difference in tread diameters being such as to attain a speed reduction in the traction power train extending between the rotary members, thus making possible the use of rotary members of relatively small diameters in the interest of space conservation.

Still further, according to the present invention, the dual tread idler wheel employed is designed for cooperation with the turntable in such a manner that only a portion thereof, i.e., only one of the traction treads associated therewith, is confined within the encompassing area of the depending turntable flange provided on the turntable, the other tread projecting radially outwardly beyond the cylindrical confines of the turntable flange in all positions of the idler wheel. By such an arrangement, the height of the turntable flange may be maintained relatively small so that the depth of the usual depressed well portion on the phonograph base plate may be maintained at a minimum, thus increasing the available space within the phonograph housing beneath the turntable.

The present invention further embodies a novel drive wheel construction and a novel actuating mechanism which cooperates with the drive wheel construction in such a manner as to serve the dual function of effecting the necessary shifting movements of the drive wheel to attain the desired turntable speed changes and of causing a temporary retraction of the idler wheel from tractional engagement with the turntable during the course of such speed changes. Finally, the invention still further embodies a novel manually operable control mechanism which cooperates with the drive and idler wheel actuating mechanism through the medium of a single combined torque and thrust rod to effect the proper movements of the actuating mechanism for any selected turntable speed. The torque and thrust rod constitutes the sole connection between the manually operable control mechanism and the drive and idler wheel actuating mechanism, rotary motion of the rod effecting speed changes and axial shifting of the rod effecting idler wheel retraction. By such an arrangement, selective placement of the manual control mechanism on the phonograph base plate at various

points remote from the turntable at conveniently accessible locations may be resorted to, thus accommodating a wide variety of base plate or cabinet designs.

The provision of a phonograph possessing the advantageous features briefly outlined above being among the principal objects of the invention, another important object is the provision of a speed change mechanism and control instrumentalities therefor wherein many of the principal operative component parts thereof are formed of light sheet metal stampings or are molded from a suitable plastic material such as a polyethylene derivative or the like, thus contributing toward economy of manufacture, and, additionally, in the case of certain of the moving parts which are formed of plastic material, reducing friction to a minimum, eliminating the necessity for frequent oiling of the parts, and providing for long life of these moving parts.

Another object of the invention, in a phonograph of this type, is to provide a control mechanism for effecting turntable speed changes, the control mechanism embodying a combined rotatable and axially shiftable torque and thrust rod which is movable to various operating positions to effect the speed changes under the control of a manual or finger-operated control lever, together with novel spring-biasing means whereby the rod is normally unbiased in any one of its effective positions, the spring-biasing means serving to apply biasing force to the rod only after the control lever has been initially manipulated to effect a turntable speed change. By such an arrangement, the various operative parts of the mechanism are not subjected to the high degree of initial counter-torque which frequently accompanies efforts to shift the control levers of conventional phonograph speed change mechanisms, and a more uniform shifting action than has heretofore been possible is attained.

The provision of a phonograph which is of relatively simple construction so that it may readily be dismantled and reassembled for purposes of inspection of parts, replacement thereof or repair, one which is comprised of a minimum number of moving parts and which, therefore, is unlikely to get out of order; one which is rugged and durable and which will withstand rough usage; one which is compact in its design; one which is smooth and silent in its operation; and one which otherwise is well adapted to perform the services required of it, are further desirable features which have been borne in mind in the production and development of the present invention.

Numerous other objects and advantages of the invention, not at this time enumerated, will become more readily apparent as the following description ensues.

In the accompanying five sheets of drawings forming a part of this specification, a preferred embodiment of the invention has been shown.

In these drawings:

FIG. 1 is a plan view of a phonograph turntable assembly embodying the principles of the present invention, certain parts being broken away and other parts being shown in section to more clearly illustrate the invention;

FIG. 2 is a perspective view of the assembly of mounting plate, electric motor, idler wheel and four-speed driving mechanism;

FIG. 3 is a fragmentary plan view of the assembly shown in FIG. 2, illustrating the idler wheel in one of its operative positions wherein the periphery thereof bridges the distance between the turntable flange and the upper end of the armature shaft so that the turntable is driven at the lowest rate of speed of which it is capable;

FIG. 4 is a fragmentary plan view similar to FIG. 3 showing the idler wheel in its inoperative or retracted position as a preliminary to shifting of the drive wheel into one of the four positions of which it is capable of assuming;

FIG. 5 is a side elevational view of the structure shown in FIG. 3 and showing the manual control mechanism

therefor operatively connected thereto, the latter mechanism being shown in vertical section;

FIG. 6 is a side elevational view, partly in section, similar to FIG. 5 showing the idler wheel and drive wheel in peripheral engagement, each with the other, for effecting a second or low intermediate speed of rotation of the turntable;

FIG. 7 is a side elevational view similar to FIG. 6 showing the drive wheel and idler wheel in operative engagement, each with the other, for effecting a third or high intermediate speed of rotation of the turntable;

FIG. 8 is a side elevational view similar to FIG. 7 showing the drive wheel and idler wheel in operative engagement, each with the other, for effecting a fourth or high speed drive of the turntable;

FIG. 9 is a sectional view taken substantially along the line 9—9 of FIG. 5;

FIG. 10 is a sectional view taken substantially along the line 10—10 of FIG. 5;

FIG. 11 is a perspective view of a manual control assembly employed in connection with the present invention and showing the same operatively applied to a crank shaft by means of which rotary motion is transmitted from the assembly to the speed change mechanism associated with the turntable;

FIG. 12 is a sectional view taken substantially along the line 12—12 of FIG. 9 showing the crank shaft in one of the normal positions of which it is capable of assuming while the turntable is being driven;

FIG. 13 is a sectional view similar to FIG. 12 showing the crank shaft in a position which it assumes upon initial movement thereof toward an intermediate position preparatory to effecting a speed change;

FIG. 14 is a sectional view similar to FIGS. 12 and 13 showing the crank shaft in an intermediate position slightly displaced from the position of FIG. 13;

FIG. 15 is a sectional view taken substantially along the horizontal plane indicated by the line 15—15 of FIG. 2;

FIG. 16 is an end elevational view of the structure shown in FIG. 15;

FIG. 17 is an enlarged sectional view taken substantially on the vertical plane indicated by the line 17—17 of FIG. 2;

FIG. 18 is a sectional view taken substantially along the line 18—18 of FIG. 17; and

FIG. 19 is an exploded view of the structure shown in FIGS. 17 and 18.

GENERAL CONSIDERATIONS

The phonograph which is shown in FIG. 1, embodies the preferred form or embodiment of the novel four-speed turntable driving mechanism of the present invention. It is adapted to reproduce sound from disk-type records and comprises a horizontally extending, substantially rectangular base plate 10, a turntable 12, a tone arm 14 and, in addition, a unitary turntable drive assembly 16 (FIG. 2) which, as hereinafter pointed out in detail, serves to drive the turntable selectively at various speeds, depending upon the character or design of the record to be played. Present day commercial phonograph records are predicated upon four basic or standard turntable speeds including a low speed of 16½ r.p.m., an intermediate low speed of 33½ r.p.m., an intermediate high speed of 45 r.p.m., and a high speed of 78 r.p.m. These speeds may vary slightly above and below the various standards selected by manufacturers and the mechanism of the present invention for attaining various turntable speeds has been designed with these standard speeds in mind, although it will be understood that the invention may with but slight modification be employed for the attainment of other low, intermediate low, intermediate high and high turntable speeds. Irrespective, however, of the selected turntable speeds, the essential features of the invention are at all times preserved.

The various parts of the phonograph with the exception of the turntable driving assembly, are conventional or standard. The base plate 10 is in the form of a one-piece sheet metal stamping and has in its central portion a depressed shallow circular wall part 18 which is of slightly greater diameter than that of the turntable 12. The corner portions of the base plate 10 are provided with fixed depending legs 20 for supporting the base plate in an elevated position on the housing structure (not shown) for the phonograph. The turntable 12 is located for the most part within the shallow well 18 of the base plate 10 and embodies on its central portion a depending hub (not shown) and on its outer marginal portion a depending annular flange 22. The aforementioned hub on the central portion of the turntable surrounds the base of an upstanding spindle 24 and serves to support the turntable rotatably. The depending annular flange 22 extends at right angles to the turntable and provides on its inner periphery a friction-type driving surface 26. The spindle 24 is adapted to support a stack of records in an elevated position and in centered relation with respect to the turntable and has associated with it conventional ejector mechanism (not shown) for automatically permitting the lowermost record of the stack to drop toward the turntable by gravity after the playing of a previously dropped record on the turntable. The tone arm 14 of the phonograph is disposed above the turntable and has one end thereof connected to the upper end of a pedestal 28 on one corner of the base plate 10 so that it is capable of swinging laterally relatively to the turntable. The distal end of the tone arm is provided with a needle (not shown) for engaging the sound track of the record to be played as is conventional in the art.

THE TURNTABLE DRIVE ASSEMBLY

The unitary turntable drive assembly 16 is located under the outer portion of the turntable 12 and comprises a mounting plate 30, an electric motor 32, a laterally movable idler wheel assembly 34, a vertically slideable stepped drive wheel 36, fork and groove type mechanism 38 for sliding the drive wheel vertically upwards and downwards, and manually operable control mechanism 40 for actuating the fork and groove mechanism 38, including automatic means whereby, as a preliminary to sliding movement of the drive wheel, the idler wheel assembly is temporarily shifted out of its hereinafter described operative position.

The mounting plate 30 of the assembly 16 is in the form of a one-piece stamping and is substantially square. It is located beneath a cutout 42 in the depressed part 18 of the phonograph base plate 10.

The electric motor and its mounting

The motor 32 is of conventional construction and is of the alternating current type having a laminated stator structure 44 which is set upon posts 46 riveted as at 48 to the mounting plate 30 in such a manner that the stator structure is maintained spaced a small distance beneath the mounting plate. A series of suspension posts 50, of which there are preferably three in number (see FIGS. 3, 4 and 5) are riveted as at 52 to the mounting plate 30 project upwardly from the latter, and are formed adjacent their upper ends with shoulder-forming ledge portions 54 which underlie rubber grommets 56 seated within openings 58 provided in the well portion 18. The upper ends of the post 50 project upwardly through the openings 58 and are suspended from the grommets 56 by means of half-moon retainers 60 (FIG. 4). A field coil 62 best seen in FIG. 5 surrounds one leg of the stator 44 and a rotatable armature 64 (FIG. 5) is fixedly secured to the lower portion of a vertically extending shaft 66. The lower end of the armature shaft is journaled in a bearing 68 supported in a bracket 70 secured by screws 72 to the underneath side of the stator 44. The upper portion of the armature shaft projects upwardly above the

mounting plate 30 and is rotatably supported in a bearing 74 carried by the mounting plate. The extreme upper end region of the armature shaft 66 terminates a small distance inward of the depending annular flange 22 on the turntable 12 of the phonograph for purposes that will be made clear presently. The electric motor 32 is of the constant speed type and operates when electric current is supplied to the field coil 62 to effect rotation of the armature shaft 66.

10

The idler wheel assembly

The idler wheel assembly 34 is in the form of a rigid spool-like unit including a relatively large lower friction wheel 76, a relatively small upper friction wheel 78 and a spacer member 80 extending between the two wheels. As seen in FIG. 7, each wheel is provided with a grooved periphery 82 within which there is seated a resilient rubber anti-friction band or traction tread 84. As will be pointed out in greater detail presently, the traction tread 84 on the smaller upper wheel 78 is designed for frictional engagement with the inside cylindrical surface 26 of the turntable flange 22 while the traction tread on the larger lower wheel 76 is designed for selective engagement with the extreme upper end regions of the armature shaft 66 and the stepped periphery of the drive wheel 36.

The idler wheel assembly 34 is floatingly mounted on the depressed well portion 18 of the base plate 10 for swinging movements universally in all directions in a horizontal plane immediately above the level of the well portion. The overall vertical extent of the assembly 34 is somewhat less than the height of the annular flange 22 on the turntable 12 so that the assembly 34 may be positioned within the circumferential confines of the turntable flange and be interposed between the plane of the turntable and the plane of the well bottom. The idler wheel assembly 34 is freely rotatable upon a vertical stud or shaft 90 carried at the outer end of a floating arm 92, the inner end of the arm being pivoted as at 94 to the distal end of a supporting link 96. The proximate end of the link is pivoted on a fixed stud 98 which extends upwardly from the well 18. The assembly 34 is thus capable of moving in a horizontal plane in all directions within limits which are defined by the combined lengths of the link 96 and arm 92.

45

THE THRUST BRACKET

The cut-out or hole 42 (FIG. 1) is of irregular contour and is formed with a pair of opposed, parallel, straight linear edge portions 100 and 102 (FIGS. 3 and 4) which, in effect, constitute guide rails for constraining the limited horizontal sliding movements of a thrust bracket assembly 103 including a thrust bracket proper 104, the details of which best appear in FIG. 2. The bracket 104 is capable of limited sliding movement in the transverse directions indicated by the arrows in this view.

The thrust bracket proper 104 is formed as a sheet metal stamping and it is generally of inverted G-shape cross section, including as it does a vertical leg 106, a laterally turned lower flange 108, a laterally turned upper flange 110, and a depending reentrant flange 112. The opposite edges of the vertical leg 106 are notched as at 114 to receive the opposed edges 100 and 102 of the cutout 42, the notches and edges constituting a sliding mounting for the bracket 104 as a whole. A coil spring 116 serves to maintain the bracket 104 in a retracted position.

65

Geometrical Speed Change Considerations

Referring now to FIGS. 1, 2 and 3, a coil spring 118 extends between the bracket 104 and arm 92 and normally urges the arm in a counterclockwise direction as viewed in FIGS. 3 and 4. Due to the effective linear extents of the link 96 and floating arm 92 and the relative locations of the pivot post 98 and armature shaft 66, as well as the respective diameters of the large idler wheel 76, the small idler wheel 78 and the turntable 12, the spring 116 exerts a pulling force on the pivot stud 90 hav-

70

78

ing a directional vectorial component of motion which draws the periphery of the large wheel 76 against the armature shaft 66 and simultaneously draws the periphery of the small wheel 78 against the turntable flange 22 whereby the rotational movement of the armature shaft 66 is transmitted through the idler wheel assembly 34 to the turntable flange, and consequently to the turntable as a whole. Since the diameter of the armature shaft 66 at the upper end thereof is appreciably less than the diameter of the large wheel 76, since the diameter of the small wheel 78 is less than the diameter of the large wheel 76, and since the diameter of the small wheel 78 is appreciably less than the diameter of the turntable flange 22, a four-fold speed reduction based upon the linear extents of the relative circumferences of the parts 66, 76, 78 and 22 is attained.

Thrust Bracket and Idler Wheel Connections

As best seen in FIGS. 3 and 4, the idler wheel assembly 34 is movable between an advanced operative position wherein the same bridges the distance, so to speak, between the armature shaft 66 and the depending turntable flange 22 to interconnect these two rotatable bodies in driving relationship, and a retracted inoperative position wherein the same is out of contact with the depending flange 22 so that a driving connection between the two rotatable bodies no longer exists. The advanced position of the assembly is illustrated in FIG. 3 while the retracted position of the assembly is illustrated in FIG. 4. The movements of the assembly between its two extreme positions take place under the control of the shifting movements of the thrust bracket 104 which, as heretofore described, is shiftable laterally within the hole or cut-out 42 in the well portion of the base plate 10. Accordingly, a rigid thrust rod 120 has one end thereof loosely disposed in a slot 122 provided in (see also FIG. 7) the upper flange 110 of the thrust bracket 104 and has its other end loosely attached as at 124 to a medial region of the arm 92. Thus, it will be seen that when the thrust bracket 104 assumes its extreme right hand position as shown in FIG. 3, the idler wheel assembly 34 will be released by the thrust rod 120 so that the spring 116 will become effective to draw the assembly to its operative position wherein the small idler wheel frictionally and tractionally engages the inside friction surface of the turntable flange 22 in driving relationship. When the thrust bracket 104 is moved toward its extreme left hand position as shown in FIG. 4, the thrust rod 120 is under compression and causes the floating arm 92 to be moved in a clockwise direction so as to cause the large idler wheel 76 to "ride out," so to speak, on the rotating periphery of the armature shaft 66 and move away from the depending turntable flange 22 so that the turntable drive is discontinued. As will be pointed out presently, this inoperative position of the idler wheel assembly 34 is merely a temporary position which obtains during speed change operations.

THE DRIVE WHEEL ASSEMBLY

Referring now to FIGS. 17, 18 and 19 wherein the details of the vertically shiftable composite drive wheel 36 are best illustrated, this drive wheel is comprised of three parts including a stepped traction hub or sleeve 130 and two disk-like dished ring members 132 and 134 which define therebetween a groove 136 designed for cooperation with a shifting fork member 138 forming a part of the previously mentioned fork and groove mechanism 38. The hub 130 is preferably formed of metal while the ring members 132 and 134 are preferably formed of a suitable plastic material having good antifriction characteristics and capable of being molded to shape. The ring members 132 and 134, in effect constitute a composite shift collar for the drive wheel. The hub 130 is formed with a central bore 140 which is frictionally and slidably received over the armature shaft 66. The upper end region of the shaft 66 is formed with a re-

duced portion 142 defining a relatively wide groove a slight distance below the upper end of the shaft and this reduced portion 142 is designed for engagement with the periphery of the large idler wheel 76 when the turntable is being driven at its low speed. The groove afforded by the reduced portion 142 is adapted selectively to be bridged by the positioning of different vertical extents or sections of the stepped hub 130, such sections presenting outer cylindrical traction surfaces of progressively increasing diameters from top to bottom. Accordingly, the hub is formed with an upper section 144 of relatively small diameter, an intermediate section 146 of larger diameter, and a section 148 of still larger diameter. The hub 130 is vertically shiftable on the armature shaft 66 in such a manner that the three sections 144, 146 and 148 may be moved selectively into register with the groove afforded by the reduced portion 142 of the armature shaft and consequently into horizontal register with the periphery of the large idler wheel 76 of the idler wheel assembly 34 so that the latter, under the influence of the spring 116, will be drawn into tractional engagement with these various hub sections. The respective diameters of the sections 144, 146 and 148 are designed according to engineering expediencies, so that the turntable 12 will attain an intermediate low speed of 33½ r.p.m. when the large idler wheel 76 is in tractional engagement with the section 144, so that it will attain an intermediate high speed of 45 r.p.m. when the idler wheel 76 is in tractional engagement with the section 146, and so that it will attain its high speed of 78 r.p.m. when the idler wheel 76 is in tractional engagement with the section 148. The diameter of the reduced portion 142 of the armature shaft 66 is such that when it is in tractional engagement with the large idler wheel 76, the turntable will rotate at its lowest rate of speed, namely 16½ r.p.m. Obviously, various turntable speeds other than those selected herein for illustrative purposes may be attained by varying the relative diameters of the various hub sections 144, 146 and 148 and the diameter of the reduced portion 142 of the armature shaft 66.

Still referring to FIGS. 17, 18 and 19, the vertical position or plane of the composite drive wheel assembly 36 is adapted to be maintained against the gravitational forces acting upon it by means of a pair of spring fingers 150 which are in the form of flat leaf springs which project upwardly from diametrically opposed points on the periphery of a collar 152 which may be crimped on a serrated or otherwise roughened portion 154 provided on the armature shaft immediately above the mounting plate 30. The lower ends of the leaf springs are turned laterally as at 156 and are clamped to the underneath surface of the collar 152 by offset clamping straps 157. The fingers 150 extend through respective slots 158 provided at diametrically spaced points in both plastic ring members 132 and 134 and a resilient split ring 161 interposed between these members and surrounding the hub 130 bears outwardly against the inner faces of the fingers 150 and serves to normally spread the same apart and into frictional engagement with the outside edges of the slots 158. The outside faces of the fingers 150 are serrated as at 159 (FIG. 19) to enhance the frictional characteristics of these faces so that the spreading force of the fingers will serve to maintain the plastic disks or rings 132 and 134 at any given level to which they may be moved under the control of the fork member 138.

THE SHIFTING FORK ASSEMBLY

Referring now to FIGS. 2, and 5 to 8, inclusive, the fork member 138 by means of which the position of the drive wheel assembly 36 may be shifted vertically along the axis of the armature shaft 66 is in the form of a generally C-shaped sheet metal stamping which is carried by and movable bodily with the laterally shiftable thrust bracket 104 but which is itself vertically shiftable within the bracket 104. The fork member 138 includes a vertical leg 160, an upper laterally extending flange 162,

a lower laterally extending flange 164 and a downwardly offset fork proper 166 on the latter flange. A pair of aligned holes are provided in the flanges 162 and 164, respectively, and a vertical post 169 has its end regions anchored in the flanges 108 and 110 of the thrust bracket 104 and passes through these holes so that the fork member 138 is vertically slidable within the thrust bracket. The vertical leg 106 of the thrust bracket 104 is slotted as at 172 and the side edges of the slot serve to confine the vertical leg 160 of the vertically shiftable fork member between the same so that turning movement of the fork member on the post 169 is prevented.

It is to be noted that the fork member 138 is movable from an extreme elevated position such as has been illustrated in FIG. 8, through two intermediate positions such as have been shown in FIGS. 6 and 7, to a lowermost position such as has been illustrated in FIG. 5, and vice versa. The fork proper 166 is at all times in register with and extends into the groove which exists between the two plastic disks 132 and 134 so that the drive wheel assembly 36 is constrained to follow the vertical shifting movements of the fork member 138.

In the lowermost position of FIG. 5, the sections 144, 146 and 148 of the hub 130 are all out of register with the groove defined by the reduced portion 142 of the armature shaft 66 so that the large idler wheel 76 may engage the reduced portion 142 under the influence of the spring 116 as previously described. In this position of the drive wheel assembly 36, the turntable will be driven at its low speed of 16½ r.p.m.

In the intermediate position of FIG. 6, the section 144 of the hub 130 will be in register with the groove defined by the reduced portion 142 of the armature shaft 66 so that the large idler wheel 76 may engage the cylindrical surface of the section 144 and cause the turntable to be driven at its intermediate high speed of 33½ r.p.m.

In the intermediate position of FIG. 7, the section 146 of the hub 130 will be in register with the groove defined by the reduced portion 142 of the armature shaft 66 so that the large idler wheel 76 may engage the cylindrical surface of the section 146 and cause the turntable to be driven at its intermediate high speed of 45 r.p.m.

In the upper position of FIG. 8, the section 148 of the hub 130 will be in register with the groove defined by the reduced portion 142 of the armature shaft 66 so that the large idler wheel 76 may engage the cylindrical surface of the section 148 and cause the turntable to be driven at its high speed of 78 r.p.m.

THE COMBINED TORQUE AND THRUST ROD

Referring now to FIGS. 3, 4 to 8, inclusive, 15 and 16, vertical shifting movements of the fork member 138 is adapted to be effected under the direct control of a combined torque and thrust rod 174 which extends between the fork member and the previously mentioned manually operable control instrumentalities 40 of FIGS. 9 to 14, inclusive.

The combined torque and thrust rod 174 has its left hand end region rotatably supported in a laterally turned ear 180 while the right hand end of the rod is supported in a pivoted cage member 182 (FIG. 5) forming an element of the mechanism 40 subsequently to be described. The rod is supported in a horizontal position a slight distance below the horizontal plane of the bottom wall of the well 18 in the base plate 10. The left hand end region of the rod 174 is formed with a crank arm 183 carrying a crank pin 184 which projects through a slot 186 (FIGS. 2, 15 and 16) provided in the vertical leg 160 of the vertically shiftable fork member 138. The crank arm 183 is movable bodily with the thrust rod through an angle of approximately 45° between the lowered position thereof shown in FIG. 5 wherein the crank pin 184, and consequently the fork member 138 is in its lowermost position, and the elevated position shown in FIG. 8 wherein the crank arm 183 projects through the cut-out or hole

42 so that the crank pin 184 is disposed wholly within the well 18. The crank arm 183 in moving from either extreme position to the other extreme position swings throughout an angle of approximately 45°.

THE MANUALLY OPERABLE CONTROL MECHANISM

Referring now to FIGS. 9 to 14, inclusive, wherein the manually operable control mechanism 40 is best illustrated, this control mechanism is in the form of a unitary assembly of parts which is carried on the base plate 10 adjacent one corner thereof as shown in FIG. 1.

The cradle

15 The assembly 40 involves in its general organization a cradle member 200 (FIG. 11) which is preferably formed of molded plastic material such as a polyethylene condensation product in the form of an inverted hollow generally frusto-pyramidal four-sided structure wherein the large base of the pyramid is open and is bounded by a horizontal marginal flange 202, which seats squarely upon the upper face of the base plate. The inverted truncated pyramidal portion of the structure projects downwardly through a rectangular slot or opening 304 (FIGS. 9 and 10) provided in the base plate 10, thus providing a four-sided open well or socket 206 having a vertical wall 208, an opposed inclined wall 210, sloping side walls 212 and 214, and a generally flat bottom wall 216. The walls 208 and 210 and 216 are provided with semi-circular cut-away portions 218 in alignment with similar cut-away portions 220 provided in a series of angular web parts 222 at the bottom of the pyramidal structure exteriorly of the latter. The marginal flange 202 is formed with downwardly extending lugs 224 which extend through holes 226 in the base plate 10. The holes and lugs serve to center the cradle member 200 in position within the opening 204.

40 The various semi-circular cut-away portions 218 and 220 afford curved bearing surfaces which partially surround a cylindrical tubular extension or pivot shaft 225 which is integrally formed on the previously mentioned cage member 182. The axis of the pivot shaft 225 constitutes the axis of pivotal swinging movement of the cage member 182. The shaft 225 (FIG. 10) extends horizontally and the upper region thereof projects into the wall or socket 206 through an opening 230 provided in the socket bottom wall 216 by virtue of the cut-away portions 218. An actuating finger 232 is formed on the shaft 225 and extends radially outwardly therefrom and projects upwardly in the well or socket. The actuating finger 232 is capable of being swung bodily with the cage member 182 throughout an angle of approximately 45° within the well or socket 206 so that it selectively may assume four different positions of adjustment representing the four different speed changes of which the turntable 12 is capable, all in a manner that will be made clear presently.

The cage member

60 The cage member 182, including the shaft portion 225 and actuating finger 232, is of integral construction, the same preferably being formed of a suitable moldable plastic material such as polyethylene. The member 182 includes a cage proper (FIGS. 9 and 10) 234 of rectangular box-like configuration including a top wall 236 having a groove 238 formed therein, and a back wall 240. The right hand end of the combined torque and thrust rod 174, as viewed in FIG. 5, projects into the cage proper 234, extends along the groove 238, is turned laterally as at 242 and extends along the back wall 240 to a point adjacent the bottom of the cage, from whence it is again turned laterally to provide an offset extension 244 having an upturned end 246 (see also FIGS. 3 and 4). A pair of triangular webs 248 (FIGS. 9 and 11) formed on the back wall 240 straddle the downturned portion 242 of the rod 174 and constrain the same to follow the swinging movements of the cage proper.

Referring now to FIGS. 5, 9 and 10, the cylindrical pivot shaft portion 225 of the cage member 182 is maintained in position within the various semi-circular cut-away recesses 218 and 220 by means of a vertically extending plate 250 which is generally of V-shape contour as best seen in FIG. 10 and having laterally turned ears 252 which may be riveted, welded or otherwise secured to the underneath face of the base plate 10. The trough of the V-shaped plate 250 is rounded as at 254 and has a laterally turned cradle flange 256 which underlies the cylindrical pivot shaft 225 and serves to support the same in position within the various cut-away recesses 218 and 220.

As best seen in FIGS. 3, 4, 9 and 10, the vertically disposed plate 250 is formed with a series of four spaced slots or openings 258 which have been additionally alphabetically designated at L, IL, IH and H, respectively. These slots are radially disposed relative to the longitudinal axis of the rod 174 and assume spaced positions in the plate 250 which are such that they may selectively register with the upturned end 246 (FIG. 10) of the rod 174 upon angular positioning of the laterally turned portion or crank arm provided on the latter. The slot designated L is adapted to receive the upturned end 246 of the rod 174 when low turntable speed is effective. The slot designated IL is designed to receive the end 246 when intermediate low turntable speed is effective. The slot designated IH receives the end 246 to effect intermediate high turntable speed. The slot designated H receives the end 246 when high turntable speed is effective.

The spring retainer

Still referring to FIGS. 9 to 14, inclusive, the cage proper 234 is formed with a laterally extending ledge portion 260 which serves as an anchoring platform for a unitary spring retainer 262 having generally parallel extending spring fingers 264 and 266 which project forwardly beyond the back wall 240 and through the open cage structure 234, as best seen in FIGS. 12, 13 and 14. The fingers 264 and 266 straddle the depending portion or crank arm 242 of the rod 174 and, forwardly of the crank arm 242, these fingers are turned inwardly as at 268 so that they cross each other, and are turned outwardly as at 270 so that they again cross each other in the distal regions of the fingers. The two fingers 264 and 266, together with the inturned portions 268, constitute in effect an extensible closed loop 272 which completely encompasses the crank arm 242 and restrains the longitudinal shifting movements of the combined torque and thrust rod 174 in a manner that will be made clear presently.

It is to be noted from an inspection of FIGS. 5 and 12 to 14, inclusive, that the spring fingers 264 and 266 exert opposed inwardly directed forces on the laterally turned crank arm 242 of the rod 174 when the upturned end 246 of the rod is in its home position within any one of the slots 258. This inwardly directed force on each side of the crank arm 242 serves to center the upturned end 246 in the various slots without offering any degree of longitudinal pull on the rod 174 as a whole. In other words, the inturned portions 268 of the spring fingers 264 and 266 do not exert their camming action on the crank arm 242 while the end of the rod is seated within the holes and these latter portions 268 become effective only after the upturned end of the rod has moved outwardly on the bevelled edges of the slots 258. By such an arrangement, there are no initial frictional forces tending to resist the application of manual torque to the actuating finger 232 (FIG. 10) and turntable speed changes may be easily effected without undue forcing of the parts.

OPERATION

As may be ascertained from inspection of FIGS. 3, 4, 10, and 12 to 14, inclusive, manipulation of the actuating finger 232 to effect swinging movement of the cage proper 234 will also cause swinging movement of the

crank arm 242 so that the combined torque and thrust rod 174 will be turned bodily as a whole about its longitudinal axis, thus causing swinging movement of the crank arm 183 (FIG. 7) and effecting speed change operations as previously described. Such swinging movement of the crank arm 242 will be accompanied by lateral shifting of the rod 174 to the left, as viewed in FIGS. 3 and 4, so that the thrust bracket 104 will be likewise shifted and the large idler wheel 78 withdrawn from frictional engagement with the inside tread surface of the depending turntable flange 22 as previously set forth. Such shifting movement of the rod 174 takes place during each in-between position of the crank arm 242 when the upturned end 246 of the rod 274 moves out of one of the slots 258 and travels on the inside face of the depending plate 250. The longitudinal shifting action of the rod 174 is clearly illustrated in FIGS. 12, 13 and 14 wherein the cage proper 234 moves in the direction indicated by the arrows in these views to cause the rod end 246 to be withdrawn from the slot L and deposited in the adjacent slot IL.

It is to be noted that walls of the various slots 258 are bevelled and this fact, coupled with the fact that the contour of the upturned end 246 of the rod 174 is cylindrical, effects a camming action on the rod end 246 when torque is applied to the cage member tending to swing the crank arm 242 in either direction. Additionally, a second camming action takes place between the bevelled edges of the triangular webs 248 and the crank arm 242 tending to "lift" the rod end 246 from the slots. In FIG. 12 the rod end 246 is shown as being squarely seated within the slot H to effect a high speed of rotation of the turntable 12. In FIG. 13, the rod end 246 is shown at the commencement of a speed change wherein in the same rides outwardly of one of the bevelled side edges of the slot L. At such time, the camming action on the rod 174 as a whole is such as to impart a slight axial shifting movement to the rod whereupon the crank arm 242, within the closed loop 272, moves against the inturned portion 268 of the spring finger 266 and deflects the latter finger to the right as seen in this view. In this position of the finger 266 and crank arm 242, a reverse thrust is exerted upon the thrust rod 174 as a whole tending to maintain the rod end 246 in frictional engagement with the bevelled surface of the edges of the slot L.

As the lower end of the cage proper 234 continues to move toward the left as viewed in FIG. 13, it rides outwardly on the bevelled edge of the slot and travels on the plane inside face of the depending plate 250 whereupon the rod 174 is shifted axially to the left as viewed in FIGS. 3 and 4 so that the thrust bracket, through the medium of the thrust link 120 (FIG. 4) is shifted to the left and the small wheel idler wheel 78 is moved away from the depending turntable flange 22. This position of the idler wheel 78 is a temporary one and obtains as long as the upturned end 246 of the rod 174 remains in contact with the planar face of the depending plate 250.

Upon continued movement of the cage proper toward the left as viewed in FIG. 14, the adjacent slot IL is encountered by the upturned end 246 of the rod 174 and this end of the rod drops in slot IL under the impelling influence of the camming action between the inturned portion 268 of the spring finger 266, whereupon the rod 174 as a whole is shifted to the right as viewed in FIGS. 3 and 4, thus carrying the thrust bracket 104 to the right and releasing the free floating arm 92 so that the latter, under the influence of the spring 116, restores the small idler wheel 78 to its operative position of frictional tractive engagement with the inside friction surface on the depending annular flange 22 of the turntable 12.

It is believed that the above description of the action of the spring finger 266 during swinging motion of the cage proper 234 in a clockwise direction as viewed in FIG. 9 will obviate the necessity of describing the action of the

spring finger 264 on the crank arm 242 when the latter swings bodily with the cage proper 234 in a counterclockwise direction to effect removal of the rod end 246 from any one of the slots 258 to the next adjacent slot for effecting a speed change of the turntable 12 for speed decreasing purposes. It is deemed sufficient to state that the inwardly turned portion 268 of the spring finger 264 will at all times exert a camming action on the crank arm which biases the combined torque and thrust rod 174 toward the depending plate 250.

The herein described phonograph is simple in its design and construction and efficient in operation and this is directly attributable to the design, arrangement and mode of operation of the particular four-speed driving mechanism and the manual control instrumentalities therefor. In view of the fact that the drive wheel assembly 36, the idler wheel assembly 34 and the manual control mechanism 40 are composite or unitary structures capable of being preassembled and installed in the phonograph construction bodily as independent units, and in view of the fact that the principal component parts of these various assemblies are either in the form of sheet metal stampings or molded plastic bodies, the phonograph as a whole may be manufactured at a relatively low cost.

The invention is not to be limited to the exact arrangement of parts shown in the accompanying drawings or described in this specification as various changes in the details of construction may be resorted to without departing from the spirit of the invention. Only insofar as the invention has particularly been pointed in the accompanying claims is the same to be limited.

Having thus described the invention what I claim as new and desire to secure by Letters Patent is:

1. In a phonograph of the type that embodies a horizontally disposed record-supporting turntable with a depending flange on its outer margin, mechanism operative to drive the turntable at different speeds and comprising a base plate beneath the turntable, a horizontally disposed idler wheel rotatably mounted on said plate against vertical displacement and constrained to move horizontally into and out of frictional engagement with the flange on the turntable, spring means normally urging the idler wheel into engagement with the flange on the turntable, a single speed electric motor mounted substantially fixedly on said base plate and embodying a vertically extending armature shaft having its upper end region terminating in horizontal register with and in the path of movement of the idler wheel and adapted when in direct engagement with the idler wheel to effect low speed drive of the turntable through the medium of the idler wheel, a rigid drive wheel having a stepped periphery providing vertically displaced cylindrical outer surfaces of different diameters respectively which are selectively movable, upon vertical shifting of the drive wheel, into horizontal register with said idler wheel, said cylindrical surfaces of different diameter being adapted, when separately in contact with said idler wheel, to effect rotation of the turntable through the medium of the idler wheel at respective driving speeds higher than said low speed drive, means providing a shift collar on said drive wheel concentric with the axis of the latter, said shift collar having an inner hub portion and an outer periphery provided with a continuous groove therearound, there being a pair of diametrically opposed holes in said hub portion, a finger-supporting collar on said armature shaft below said drive wheel, a pair of vertically extending linearly straight spring fingers having their lower ends secured to said collar and projecting upwardly through said holes respectively, a split expansion ring surrounding said armature shaft radially inwardly of said spring fingers and bearing radially outwardly against the latter for spreading the same apart and into engagement with the respective opposed edges of the holes through which the fingers extend, a fork member mounted on said base plate for vertical shifting movement and projecting into the

groove provided by said shift collar, and manually operable means for shifting said fork member.

2. In a phonograph of the type that embodies a horizontally disposed record-supporting turntable with a depending flange on its outer margin; mechanism operative to drive the turntable at different speeds and comprising a base plate beneath the turntable, a horizontally disposed idler wheel rotatably mounted on said plate against vertical displacement and constrained to move horizontally into and out of frictional engagement with the flange on the turntable, spring means normally urging the idler wheel into engagement with the flange on the turntable, a single speed electric motor mounted substantially fixedly on said base plate and embodying a vertically extending armature shaft having its upper end region terminating in horizontal register with and in the path of movement of the idler wheel and adapted when in direct engagement with the idler wheel to effect low speed drive of the turntable through the medium of the idler wheel, a rigid drive wheel having a stepped periphery providing vertically displaced cylindrical outer surfaces of different diameters respectively which are selectively movable, upon vertical shifting of the drive wheel, into horizontal register with said idler wheel, said cylinder surfaces of different diameter being adapted, when separately in contact with said idler wheel, to effect rotation of the turntable through the medium of the idler wheel at respective driving speeds higher than said low speed drive, said drive wheel including a pair of vertically displaced disk-like parts of greater diameter than the diameter of the largest cylindrical surface of said stepped periphery, there being two pairs of vertically aligned holes in said vertically displaced disk-like parts at diametrically disposed regions thereon, a collar on said armature shaft below said drive wheel, a pair of vertically extending linearly straight spring fingers having their lower ends secured to said collar and projecting upwardly through said pairs of vertically aligned holes respectively, said vertically displaced disk-like parts defining therebetween an annular groove surrounding the drive wheel, a split expansion ring disposed within said groove radially inwardly of said spring fingers and bearing radially outwardly against said fingers to bias the latter radially against the respective opposed edges of the holes through which the fingers extend, a fork member mounted on said base plate for vertical shifting movement and projecting into the groove defined by said disk-like parts, and manually operable means for shifting said fork vertically.

3. In a phonograph of the type that embodies a horizontally disposed record-supporting turntable with a depending flange on its outer margin; mechanism operative to drive the turntable at different speeds and comprising a base plate beneath the turntable, a horizontally disposed idler wheel rotatably mounted on said plate against vertical displacement and constrained to move horizontally into and out of frictional engagement with the flange on the turntable, spring means normally urging the idler wheel into engagement with the flange on the turntable, a single speed electric motor mounted substantially fixedly on said base plate and embodying a vertically extending armature shaft having its upper end region terminating in horizontal register with and in the path of movement of the idler wheel and adapted when in direct engagement with the idler wheel to effect low speed drive of the turntable through the medium of the idler wheel, a rigid drive wheel having a stepped periphery providing vertically displaced cylindrical outer surfaces of different diameters respectively which are selectively movable, upon vertical shifting of the drive wheel, into horizontal register with said idler wheel, said cylindrical surfaces of different diameter being adapted, when separately in contact with said idler wheel, to effect rotation of the turntable through the medium of the idler wheel at respective driving speeds higher than said low speed drive, means on said drive wheel defining an annular groove concentric

with the axis of the drive wheel, a thrust bracket slidably mounted on said base plate for limited horizontal sliding movement in opposite directions, a fork member mounted for independent vertical sliding movement in said bracket, guide means constraining said fork member to move bodily with the thrust bracket, said fork member including a fork proper extending into said annular groove and operable, upon vertical shifting of the fork member to effect vertical shifting of the drive wheel, a thrust rod extending between the thrust bracket and idler wheel for translating the sliding movements of the former into displacements of the latter bodily, said thrust bracket being movable between a retracted position wherein said idler wheel is in frictional engagement with the turntable flange and an advanced position wherein said thrust rod maintains the idler wheel out of frictional engagement with the turntable flange, and manually operable means for simultaneously shifting said thrust bracket horizontally and shifting said fork member vertically.

4. In a phonograph of the type that embodies a horizontally disposed record-supporting turntable with a depending flange on its outer margin; mechanism operative to drive the turntable at different speeds as set forth in claim 8 wherein said manually operable means for simultaneously shifting the thrust bracket horizontally and shifting said fork member vertically includes a combined torque and thrust rod mounted on said base plate for turning movement about a horizontal axis and for axial shifting movement along said axis, an eccentric arm on said thrust rod displaced from the axis of the latter, means establishing a connection between said eccentric arm and fork member whereby upon turning movement of the rod said fork member will be shifted vertically and upon axial shifting movement of the rod said fork member will be displaced horizontally and the horizontal displacements of the latter will be translated to the thrust bracket through the medium of said guide means.

5. In a phonograph of the type that embodies a horizontally disposed record-supporting turntable with a depending flange on its outer margin; mechanism operative to drive the turntable at different speeds and comprising a base plate beneath the turntable, a horizontally disposed idler wheel rotatably mounted on said plate against vertical displacement and constrained to move horizontally into and out of frictional engagement with the flange on the turntable, spring means normally urging the idler wheel into engagement with said flange, a single speed electric motor mounted on said base plate and having a vertically extending armature shaft the upper end of which is in horizontal register with the idler wheel and adapted when in direct engagement with the latter to effect low speed drive of the turntable, a rigid drive wheel having a stepped periphery providing vertically displaced cylindrical outer surfaces of different diameters which are selectively movable, upon vertical shifting of the drive wheel, into horizontal register with said idler wheel, means on the drive wheel defining an annular groove, a thrust bracket horizontally slidably on said base plate, a fork member mounted for independent vertical sliding movement in said thrust bracket, guide means constraining the fork member to move bodily with the thrust bracket, said fork member extending into said groove, a thrust rod connecting said thrust bracket and idler wheel for translating the sliding movements of the former into displacements of the latter bodily whereby shifting of the thrust bracket in one direction will cause withdrawal of the idler wheel from engagement with the turntable flange, a combined torque and thrust rod mounted on said base plate for both turning and axial shifting movements about and along a horizontal axis, means establishing a connection between one end of said combined torque and thrust rod and fork member whereby upon turning of the rod said fork member will be shifted vertically and upon axial shifting of the rod in one direction the fork member will be displaced horizontally with the horizontal

displacements thereof being translated to the thrust bracket through said guide means, means for turning said combined torque and thrust rod about said horizontal axis between a plurality of operative positions throughout 5 predetermined angular degrees of turning movement, and automatically operable means incident to initial turning movement of the rod from any one of its operative positions for effecting axial sliding movement of the rod.

6. In a phonograph of the type that embodies a horizontally disposed record-supporting turntable with a depending flange on its outer margin; mechanism operative to drive the turntable at different speeds as set forth in claim 10 wherein said automatic means comprises in combination a fixed eccentric crank arm on one end of the 10 rod, a vertically disposed plate extending transversely of the rod and having a series of recesses formed therein, arranged in an arcuate row and designed for selective register with said crank arm when the rod is in selected operative positions, spring means normally urging said 15 rod axially toward a retracted position wherein an end of the crank arm may enter a recess in said plate, and cooperating cam means on said crank arm and at the edge regions of said recesses whereby, upon initial turning movement of the rod as a preliminary to movement of 20 the crank arm laterally of a recess toward the next adjacent recess, the crank arm, and consequently the thrust rod, will be shifted axially against the action of said spring means.

7. In a phonograph of the type that embodies a horizontally disposed record-supporting turntable with a depending flange on its outer margin; mechanism operative to drive the turntable at different speeds as set forth in claim 11 wherein said spring means comprises a cage member mounted for swinging movements bodily with 30 said crank arm, a pair of spring fingers mounted on said cage member and straddling said crank arm on opposite sides thereof respectively, said spring fingers being formed with inwardly extending outer end regions which converge toward each other and which are normally out of 35 contact with the crank arm when the latter is in its retracted position, said crank arm, upon axial shifting movement of the rod incident to lateral shifting movement of the crank arm away from one recess moving into frictional engagement with the inwardly extending outer end 40 region of at least one of said spring fingers and being yieldingly restrained thereby.

8. In a phonograph of the type that embodies a horizontally disposed record-supporting turntable with a depending flange on its outer margin; mechanism operative to drive the turntable at different speeds and comprising a base plate beneath the turntable, a horizontally disposed idler wheel rotatably mounted on said plate against vertical displacement and constrained to move horizontally into and out of frictional engagement with the flange of the 50 turntable, spring means normally urging the idler wheel into engagement with the flange of the turntable, a single speed electric motor mounted substantially fixedly on said base plate and embodying a vertically extending armature shaft having its upper end terminating in horizontal 55 register with and in the path of movement of the idler wheel and adapted when in direct engagement with the idler wheel to effect low speed drive of the turntable through the medium of the idler wheel, a rigid drive wheel coaxial with and mounted for vertical sliding movement on said armature shaft, said drive wheel having a stepped periphery providing vertically displaced cylindrical outer surfaces of different diameters respectively which are selectively movable, upon vertical shifting of the drive wheel, into horizontal register with said idler 60 wheel, said cylindrical surfaces of different diameters being adapted, when separately in contact with said idler wheel, to effect rotation of the turntable through the medium of the idler wheel at respective driving speeds 65 higher than said low speed drive, said drive wheel including a disk-like part of greater diameter than the di- 70

diameter of the largest cylindrical surface of the stepped periphery of the drive wheel, there being a pair of diametrically opposed holes in said disk-like part, a collar mounted on said armature shaft below said drive wheel, a pair of vertically extending spring fingers having their lower ends secured to said collar and projecting upwardly through said holes respectively, and a split expansion ring surrounding the armature shaft inwardly of said spring fingers and normally bearing radially outwardly against the fingers to bias the latter against the respective opposed edges of said holes.

9. In a phonograph of the type that comprises a horizontally disposed record-supporting turntable with a depending flange on its outer margin; mechanism operative to drive the turntable at different speeds as set forth in claim 1 wherein the sides of said spring fingers which

are remote from each other are roughened to enhance the frictional characteristics of said fingers whereby said drive wheel will be maintained against the gravitational forces acting upon it in an infinite number of positions of vertical adjustment to which it may be slid on the armature shaft.
